UNITED STATES PATENT OFFICE.

HORACE D. STEVENS, OF AKRON, OHIO, ASSIGNOR TO THE FIRESTONE TIRE AND RUBBER COMPANY, OF AKRON, OHIO, A CORPORATION OF OHIO.

TUBE-MAKING MACHINE.

Application filed July 5, 1923. Serial No. 649,474.

This invention relates to tube making machines and particularly to machines for making rubberized fabric tubes from which fan belts or similar rubber articles may be cut. In particular the invention contemplates a machine for rolling the tube, applying helical wrappings thereto, removing the wrappings after vulcanization and loosening the tube on the mandrel to admit of its ready removal therefrom.

In the manufacture of fan belts of rubberized and vulcanized fabric, the sheets of fabric are rolled about a hollow steel mandrel, the sheet being of sufficient width to make two or more convolutions about the mandrel. The steel mandrel is then carried to a wrapping lathe in which it is mounted and firmly wrapped with a spiral cloth winding. From the wrapping lathe the tube and mandrel are placed in a heater of any conventional type in which vulcanization is effected. After vulcanization the mandrel and tube are taken from the heater, the wrapping removed, and the tube stripped from the mandrel and cut into desired width.

A feature of the invention consists in a novel organization in a single tube-making machine of means for loosening the tube on the mandrel and means for applying the fabric wrapper around the tube prior to vulcanization, and also removing it after vulcanization, the latter operation requiring, in the past, a separate lathe machine.

The various other features of my invention will be best understood from a description of one embodiment thereof selected to illustrate the same, it being understood, however, that my invention is not limited to such selected embodiment.

In the drawings accompanying this description:

Figure 1 is a front elevation of the machine showing the arrangement of parts for the loosening operation;

Figure 2 is a similar view to Figure 1 illustrating the arrangement for the wrapping operation;

Figure 3 is an end elevation;

Figure 4 is a cross-section through line 4-4 in Figure 1;

Figure 5 is a sectional view showing in detail the stretching operation;

Figure 6 is a detailed elevation of the end

of one of the rolls with the chuck shown in section;

Figure 7 is a plan view of the driving mechanism;

Figure 8 is an end elevation partly in section to show the ratchet and pinion mechanism for operating the upper roll.

Referring to the drawings, the usual machine standards are indicated at 2, mounted upon which is a frame 4 suitably shaped and constructed to receive and support the various working parts of the machine. Arising above the framework at each side of the machine are vertical standards 6, the same being bifurcated at their upper ends, as best shown in Figure 3, to provide a mounting 70 for idle pulleys 8.

Mounted in fixed bearings in the frame 4 are a pair of rollers 10 and 11 designed to support and rotate a mandrel 12 upon which is wrapped the cylindrical tube 14 from which the fan belts are to be cut. Above the rollers 10 and midway therebetween is a pressure roll 16, the ends of which are reduced and received in bearings 18 upon the upper ends of slides 20, the latter being constructed for vertical movement within suitable guideways formed upon the frame of the machine. The slides 20 are connected by an angle bar 22 extending above the pressure roll 16 and provided with a vertical bearing 24 for the reception of a stud 26 carrying upon its lower end a plurality of rollers 28 arranged for engagement with the peripheral surface of the pressure roll 16, thus affording a backing to take up the spring from the latter. The pressure of the rollers 28 upon the roll 16 is adjusted by a screw 30 extending through the top of the bearing 24 to bear upon the top face of the roller carrying stud.

The lower ends of the slides 20 are provided with racks 32, the teeth of which are engaged by pinions 34 which in turn mesh with pinions 36 keyed to a shaft 38, the ends of which extend beyond the frame of the machine and are provided with hand wheels 40 by means of which the shaft is rotated. It will be evident that rotation of the hand wheel will cause vertical movement of the pressure roll toward or from the mandrel. In order to lock the roll 16 in adjusted position, pawls 42 are suitably pivoted to the frame of the machine for engagement with

a ratchet wheel 43 carried by the shaft 38. A link 44 connects the tail of the pawls and provides a convenient means for swinging the pawls about their pivots to disengage them from the ratchet when it is necessary to elevate the roll 16 by rotation of the shaft 38 in a counterclockwise direction.

As a counterbalance for the pressure roll 16, weights 46 are provided, the latter being connected to the angle bar 22 by ropes 48 extending around the idle pulleys 8 carried by the standards 6 previously referred to.

As previously intimated, this invention contemplates the provision in a fan belt 15 making machine of means for applying the wrapping to the tube prior to the curing operation and removing it therefrom after the curing operation, in addition means for loosening the tube from the mandrel to 20 facilitate the stripping operation.

In the use of the illustrated machine to loosen the tube from the mandrel, the pressure roll and supporting rolls are in direct engagement with the tube in the manner 25 clearly illustrated in Figure 1.

Such an arrangement of parts, however, would not permit the application or removal of the wrapper, as will be readily understood by anyone skilled in the manufacture 30 of articles of this particular type. The novel organization of parts, whereby the wrapping operation may be readily and speedily effected by the illustrated machine, will now be described. Keyed upon the ends 35 of the rolls 10, 11 and 16 are chucks 50 which are capable of longitudinal movement along the said rolls. Each chuck is provided with a bearing surface 52 and an up-standing extending flange 54 for supporting 40 and guiding a mandrel. The bearing surface is preferably covered by a layer of rubber or other suitable material to frictionally grip the mandrel and produce rotation thereof. When it is desired to wrap the 45 tube, the chucks are moved inwardly to receive a mandrel, in the manner illustrated in Figure 2, the tube being spaced from the rollers a distance sufficient to allow the fabric wrapper to be wound therearound. A 50 curved drum 56 extends across the front of the machine, over which the fabric is drawn in the winding operation, the desired tension being obtained by the action of the operative in retarding the strip by pressing 55 it against the surface of the drum.

In order to hold the chucks 50 in either the rolling or wrapping position, spring 60 pressed locking elements 58 are mounted upon the chucks to cooperate with detents

60 provided in the surface of the rolls.

The means for rotating the rolls 10, 11 will now be described. Mounted upon suitable bearings arising from the base of the machine are horizontal shafts 62 and 64, 65 the shaft 62 being driven from any con-

venient source of power, an electric motor 66 being herein disclosed. A conventional positive clutch 70 connects the shaft 62 with the motor, and a shifting lever 72 is connected to a slide bar 72^a arranged in a 70 handy position within reach of an operative. The shaft 62 carries a gear 74 by which it is driven and a pinion 76 which mesh with a pinion 78 on the shaft 66^a driven by motor 66 and a gear 80 on the 75 shaft 64, the gears having twice the number of teeth as the pinions. Upon the shafts 62 and 64 are mounted clutch elements 82 and 84, operable by a shifting lever 86, the arrangement being such that when one 80 clutch is engaged the other is broken. On the ends of shafts 62 and 64 are sprockets 88 and 90 which drive through chains 92 and 94 sprockets 96 and 98 on the shafts of the rolls 10 and 11 respectively. 85

The manner in which the driving mechanism operates is obvious, and no further description will be given, it being noted that provision is afforded for driving the roll 10 at a high speed and the roll 11 at a low speed, the roll 10 being driven during the wrapping and unwrapping operations and the roll 11 during the building and rolling operations. 90

While the operations of the different 95 mechanisms have been set forth in the foregoing description, they may be briefly summarized as follows:

An empty mandrel is placed into the machine so as to rest on rolls 10 and 11. Rubberized fabric from a suitable supply reel (not shown) is drawn over roll 11 under the mandrel over roll 10, roll 11 being driven for this purpose, and its end is applied to the mandrel so that the fabric may be wound on the mandrel. Rotation of roll 11 is continued until sufficient fabric is wrapped onto the mandrel, it being pressed thereon by the weight of the mandrel acting against rolls 10 and 11. When the desired number of plies are wrapped on the mandrel, rotation of roll 11 is discontinued and the stock is cut, a strip of gum being applied over the exposed end of the fabric. 100

The mandrel with a green tube thereon is ready to be wrapped, the chucks 50 being accordingly placed in their inner position to engage the ends of the mandrel. The upper roll is lowered by the hand wheel 40 until the mandrel is firmly gripped by the chucks. 110

The clutch 82 is now thrown in, causing the mandrel to be rotated at a high rate of speed. The free end of the wrapping strip is started around the tube by the operative, the strip being then drawn across the drum 56 by the rotation of the mandrel until the tube has been completely wrapped, tension being applied to the wrappings by the operative. The wrapped tube is removed from the machine and cured. 115

120

125

130

After vulcanization, the mandrel with the cured tube thereon is placed in the machine with the parts as above and the wrappings are removed as will be understood. The chucks are then shoved into the outer position, and the surface of the rolls brought into direct contact with the tube. The upper roll is forced downward until the tube is gripped with a sufficient pressure. The shifting lever 86 is now thrown toward the right and the mandrel is slowly rotated through driven roll 11. This rolling action causes the tube to be stretched circumferentially and loosens the tube on the mandrel as illustrated in Figure 5. After being rolled and loosened, the tube may be readily slipped from the mandrel. The finished tube is subsequently cut into narrow belts such as used in fans of automobiles and for other desirable purposes.

Having described my invention, I claim
as new and desire to secure by Letters Pat-
ent of the United States:

1. In a machine for wrapping and loosening a tube on a mandrel, the combination of a plurality of rolls for supporting a mandrel, and mandrel gripping means on said supports, said gripping means being shiftable into and out of operative position.

30 2. In a machine for wrapping and loosening
35 a tube on a mandrel, the combination
of means for supporting and rotating the
mandrel, mandrel gripping means on said
supporting means, said gripping means be-
ing shiftable into and out of gripping en-
gagement with said mandrel, and means for
retaining the gripping means in adjusted
position.

3. In a machine for wrapping and loosening a tube on a mandrel, the combination of means for supporting a mandrel, means for gripping the mandrel, said means being

shiftable into and out of operative position, and means for stretching the tube circumferentially.

4. In a machine of the class described having, in combination, a plurality of rolls to support and rotate a mandrel having a tube wrapped thereon, a pressure roll above the supporting rolls, and chucks mounted upon the said rolls, the said chucks being slidable longitudinally of the said rolls into or out of mandrel engaging position.

5. In a machine for applying a fabric wrapper to a tube wrapped on a mandrel, having in combination, a plurality of chucks for gripping the mandrel only at its ends, means on the chucks for guiding the mandrel, means to rotate the chucks, and a retarding device over which the fabric wrapper is pulled during the wrapping operation. 55 00

6. In a machine for wrapping and loosening a tube on a mandrel, the combination of a plurality of rolls for supporting the mandrel, and means for rotating the mandrel at a comparatively high speed during the wrapping operation and at a low speed during the loosening operation. 65

7. A tube-making machine comprising in combination a pair of rolls for supporting and rotating a mandrel for applying the material of the tube thereon, and means on said rolls adapted to be selectively employed to support and rotate said mandrel in a position spaced from said rolls. 73

8. A machine of the class described comprising a pair of rolls for supporting and rotating a mandrel and a third roll movable into engagement with said mandrel on said first rolls, each of said rolls having means thereon adapted to engage and support a mandrel for rotation in spaced relation to the rolls.

HORACE D. STEVENS.
